UNITED STATES PATENT OFFICE

ARTHUR M. CAPPER, OF PITTSBURGH, PENNSYLVANIA, ASSIGNOR TO DUQUESNE STEEL FOUNDRY COMPANY, OF PITTSBURGH, PENNSYLVANIA, A CORPORATION OF PENNSYLVANIA

ANNEALING BOX

Application filed March 9, 1928. Serial No. 260,309.

In the use of annealing boxes, the boxes webs 6 extend down to a transverse web 8, have a tendency for the side walls to warp outwardly, while the longitudinal bottom edges tend to curve inwardly. Heretofore in the manufacture of cast annealing boxes it has been the practice to form various types of corrugations in the walls of the box to resist warping, but such corrugations have always been terminated in the side walls of the box above the lowermost edges thereof. It has heretofore been considered necessary to provide a substantially straight edge along the bottom of the sides and end walls of the box, these straight edges usually having a 15 bead or foot portion therealong.

According to the present invention, I propose to provide an annealing box wherein the ribbing or corrugations, or other reinforcing devices extend clear to the bottom of the 20 box rather than terminating in the walls of the box above the bottom.

My invention may be understood by reference to the accompanying drawings which show several embodiments of my invention 25 as applied to annealing boxes and in which—

Figure 1 is a side view partly in section and partly in elevation of an annealing box embodying my invention of the type wherein the side walls are formed of a plurality 30 of channel-like sections which are alternately reversed;

Figure 2 is a transverse vertical section in the plane of line II—II of Figure 1;

Figure 3 is a side view of a portion of an 35 annealing box of another type wherein the walls of the box are provided with double corrugations for bracing them;

Figure 4 is a view similar to Figure 3 showing my invention as applied to a box 40 having single corrugations; and

Figure 5 is a transverse vertical section in the plane of line V—V of Figure 4.

In the drawings, 2 designates an annealing box having side walls 3. The side walls 3 are made up of a series of inwardly turned channels 4 between which are outwardly turned channels 5. In the outwardly turned channels 5 is a bracing web structure, this structure preferably comprising a vertically 45 extending web 6, and transverse webs 7. The

webs 6 extend down to a transverse web 8, and projecting from the transverse web 8 to the bottom of the box are a plurality of short webs 9. Somewhat similar webbing structure is shown at 10 in the inwardly 55 turned channels inside the box. Extending down from the cross web 11 are a plurality of webs 12 similar to the webs 9 but reverse with respect thereto. The end walls 13 of the annealing box may also have one or more 60 channels 14 therein with bracing similar to that described.

By inspection of Figures 1 and 2 it will be seen that the channels 4 and 5 extend to the extreme lowermost edge of the box, both 65 along the side walls and at the end walls. Likewise the bracing webs 9 and 12 extend clear down to the very edge of the box.

The advantage of this arrangement resides in the fact that the bracing webs or corrugations extending clear to the lowermost 70 edges of the box resist the tendency which the edges of the box have to curl inwardly. Heretofore all such bracing has terminated above the lowermost edge so that it could not 75 effectively resist this tendency of the edges to curl inwardly. By forming a plurality of braces at 9 and 12 in the channels near the lower edge of the box, further reinforcement against this tendency of the edges to 80 curl inwardly is provided. This arrangement is more effective than where a single vertical web extending throughout the height of the channel is provided.

In the arrangement shown in Figure 3, I 85 have shown the same idea applied to a box of a different construction. In this figure, the box 15 has its side walls 16, and if desired, its end walls 17 provided with double corrugations at 18. These corrugations extend 90 clear down to the bottom edges of the box so as to brace the lower edges against inward curling. I have shown a different arrangement of the webbing 20 for this form of box, but obviously any suitable arrangement 95 of webbing may be substituted.

In the arrangement shown in Figures 4 and 5, the invention is shown as being applied to the simplest form of braced box, the box 21 having single spaced apart corrugations 100

22 in the side and end walls. These corrugations extend clear to the very edges of the side and end walls to resist the inward curling of the walls.

5 While I have illustrated the invention as being applied to different specific forms of boxes, it will be understood that the invention is applicable to various forms of braced boxes. By carrying the bracing clear down 10 to the edges of the box, the walls of the box are not only braced against bowing outwardly, but the edges are braced against curling inwardly. The construction also simplifies the casting of the box.

15 I claim:

An annealing box having alternate reverse-
ly arranged channel portions formed in its
walls and having a bracing structure be-
tween some of the alternate channels, said
20 bracing structure including a vertical web
terminating in a transverse web spaced above
the bottom of the box, and a plurality of par-
allel webs out of alignment with said verti-
cal web extending from said transverse web
25 to the bottom of the box.

In testimony whereof I have hereunto set
my hand.

ARTHUR M. CAPPER.
